[57] CLAIM

The ornamental design for a blank for an expandible envelope, substantially as shown and described.

DESCRIPTION

FIG. 1 is a top plan view of a blank for an expandible envelope embodying my new design, the bottom plan view being the same in appearance;

FIG. 2 is a front elevational edge view of my new design;

FIG. 3 is a side elevational view of my new design, the opposite side elevational view being the same in appearance; and,

FIG. 4 is a rear elevational view of my new design. The blank is of conventional thickness. The dash lines represent fold lines within the blank structure.

FIG. 2.

FIG. 1.

FIG. 3.

FIG. 4.
